APPARATUS AND CIRCUIT ARRANGEMENT
FOR CONTROLLING X-RAY TUBES

Carl Niemann and Kurt Bischoff, Erlangen, Germany, assignors to the firm Siemens-Reiniger-Werke Aktiengesellschaft, Berlin, Germany

Application May 31, 1939, Serial No. 276,650
In Germany June 25, 1938

6 Claims. (Cl. 250—93)

The present invention relates in general to apparatus and circuit arrangements for controlling X-ray tubes. More in particular, the invention relates to the control of X-ray tubes which are supplied with high tension current at both the cathode and anode; that is, both the cathode and anode are supplied with potentials far above ground potential while the tube is in operation. Under these circumstances the switching-on and off of the high tension current, desirably effected through the medium of a grid controlled discharge tube, involves a considerable problem, and difficulties are introduced which it is the object of the invention to eliminate.

In accordance with the invention, a novel circuit arrangement is provided, adapted for use either in fluoroscopy or in radiographing, and so devised that the grid controlled discharge tube employed for switching purposes during radiographing is inserted at a point where its cathode may be grounded. This permits of the use of known and relatively simple arrangements for controlling the grid of the discharge tube.

The foregoing and other advantageous features of the invention will be explained more in detail hereinafter, reference being made to the accompanying drawing, which is a diagrammatic circuit drawing showing an X-ray tube and the circuits for controlling the same in accordance with the invention.

Referring to the drawing, the X-ray tube is indicated at 1. The reference character 2 indicates a switch having position A for radiographing and position D for fluoroscopy. Two transformers 10 and 15 are shown, one of which is used in radiographing and the other in fluoroscopy, and each having a primary winding and two secondary windings on a common core. Valves or rectifiers are indicated at 5, 7, and 16. The grid controlled space discharge device, which may be a triode of known type, is indicated at 11. Two condensers are shown at 3 and 4.

The operation of the circuits during radiographing will first be described, it being assumed that the switch 2 is in position A, as shown in the drawing. A suitable source of alternating current is of course connected to the primary winding 9 of transformer 10, and the transformer is energized. The high tension secondary windings 6 and 8 accordingly supply charging current to condensers 3 and 4, respectively, through the rectifiers 5 and 7. Energy may be supplied to the X-ray tube 1 over a circuit which includes the condensers 3 and 4 in series, and the tube 11. This circuit is normally open, due to a negative

potential which is maintained on the grid of tube 11 by battery 17. By means of suitable circuits, including a timing switch 18, the negative potential on the grid of tube 11 can be replaced by a positive potential for the desired time interval. These control arrangements for the grid of a tube such as tube 11 are well known, and as they form no part of the invention they have been indicated only diagrammatically in the drawing.

During the interval that the grid of tube 11 is at positive potential with respect to ground, the before mentioned circuit for the X-ray tube is completed at the tube 11, and high tension current is supplied to the X-ray tube from the condensers 3 and 4 in series. These condensers are continuously charged from the secondary windings 6 and 8 through the half wave rectifiers.

In order to condition the apparatus for fluoroscopy the switch 2 is changed to position D. The X-ray tube 1 is now supplied with high tension current over a circuit which includes secondary winding 13 of transformer 15, the valve 16, the triode 11, now operating as a two element valve, and the secondary winding 12. The primary winding 14 is connected to a source of alternating current, as indicated. Thus a symmetrical circuit arrangement is afforded, grounded at the junction of the two valves, one of which is the same tube that is used for switching purposes during radiographing.

The invention having been described, that which is believed to be new and for which the protection of Letters Patent is desired will be pointed out in the appended claims.

I claim:

1. A high tension circuit arrangement for an X-ray tube, comprising two condensers connected to the cathode and anode of the X-ray tube, respectively, means including a grid controlled discharge tube for connecting said condensers in series, said discharge tube having its cathode grounded, and separate circuits for charging said condensers.
2. A circuit arrangement as claimed in claim 1, characterized by the provision of a transformer having two secondary windings for charging the two condensers, respectively, and two rectifiers included in the two charging circuits, respectively.
3. Control apparatus for X-ray tube, comprising a switch having radiographing and fluoroscopy positions, a high tension circuit for the X-ray tube established in the radiographing

position and including a grid controlled discharge tube having its cathode grounded, means for supplying direct current to said circuit at two points separated by said discharge tube, a high tension circuit established in the fluoroscoping position of said switch and also including said discharge tube, and means for supplying alternating potentials to said second circuit.

4. In a control apparatus for an X-ray tube, two alternative circuits for supplying high tension current to the tube, said circuits having a common section which includes a grid controlled discharge device having its cathode grounded, means for supplying direct current to one circuit at two points on opposite sides of said discharge device, means for supplying alternating voltages to the second circuit at two points on opposite sides of said discharge device, and a valve connected in the second circuit adjacent the said device with the ground connection for the cathode of said device between the said device and the said valve.

5. A circuit arrangement for supplying high

tension current to an X-ray tube, comprising two current supply sources connected in series with said X-ray tube, a connection between said sources extending from the positive pole of one source to the negative pole of the other source, a grid controlled discharge tube inserted in the connection between said sources, and a ground connection at the cathode of said discharge tube.

6. Control apparatus for an X-ray tube, comprising two alternative circuits for supplying the tube with high tension current, means for supplying unidirectional voltages to the first of said circuits, means for supplying alternating voltages to the second of said circuits, a triode included in both circuits, said triode functioning as a switching device in the first circuit and as a rectifier in the second circuit, and means for controlling the potential on the grid of said triode when it functions as a switching device in the first circuit.
